UNITED STATES PATENT OFFICE.

HARRY KELLEY, OF WILMINGTON, DELAWARE.

METHOD OF AND MEANS FOR PREPARING VENEER STOCK FOR MATCH SPLINTS.

Application filed May 21, 1924. Serial No. 714,954.

To all whom it may concern:

Be it known that I, HARRY KELLEY, a citizen of the United States, residing at Wilmington, in the county of New Castle and State of Delaware, have invented certain new and useful Improvements in Methods of and Means for Preparing Veneer Stock for Match Splints, of which the following is a specification.

10 This invention relates to the preparation of stock from which matches are produced. In the manufacture of matches from veneer strips, it is the practice to cut sheets of veneer from logs and immediately subdivide 15 the sheets into strips, the strips being, in turn, cut into splints while the veneer is moist or wet. The splints are immersed in an impregnating solution which treats the splints in such a manner that afterglow, 20 when a match is lighted, cannot occur and the danger of fire from matches carelessly thrown away is avoided. The splints thus treated are then placed in large drums where they are subjected to a tumbling operation and to heat so that they are dried, 25 and, upon emerging from the drums, they are secured in carriers which travel past tanks or vats containing the composition for the heads of the matches and into which 30 the splints are dipped to form the completed matches. This process is time-consuming and also requires installation of complicated and expensive machinery, and it is the object of my present invention to provide a 35 method whereby the complicated and costly machinery heretofore deemed necessary may be dispensed with and the time required to impregnate the veneer and place it in condition for the formation of matches will be 40 very materially lessened. One embodiment of my invention will be hereinafter fully set forth, and the novel features will be particularly pointed out in the appended claims.

In the accompanying drawing:

45 Figure 1^a is a view, partly in elevation and partly in section, of one portion of a mechanism adapted for carrying out my invention, and

50 Fig. 1^b is a similar view of another portion of the apparatus, the two views together illustrating in a somewhat conventional manner means for carrying out the complete process.

55 In carrying out my present invention, a log, indicated at 1, is secured in a veneer lathe and the lathe is operated in the man-

ner usual to cut from the log a continuous sheet of veneer, indicated at 2. A supporting table 3 is preferably arranged adjacent the veneer lathe to receive and support the 60 sheet fed therefrom, and this table may be equipped with knives to trim the side edges of the sheets if so desired. At the side of the table opposite the veneer lathe, I arrange a tank 4 which contains the impregnating composition, and upon the side of the table I provide an idler roller 5 over which the sheet of veneer passes before turning downward into the tank. Within the tank the sheet of veneer is curled or trained 65 back and forth so as to travel through the tank in a long tortuous path. At the discharge end of the tank is a drain table 7 up and over which the sheet of veneer passes to the wringing or sizing rolls 8. The drain 70 table 7 is set at an inclination to the tank so that the surplus liquid flowing from the veneer will drain back into the tank, and it will be noted that the bottom of the tank is also inclined slightly to direct the material 75 to a discharge pipe 9 whereby the tank may be easily drained when it is to be cleaned or it is desired to train the initial end of a fresh sheet of veneer through the tank before the impregnating composition is poured 80 into the same. The rollers 8 may be mounted in any convenient support and driven in any convenient manner whereby they will be caused to exert sufficient pressure to effectually smooth the surfaces of the sheet of 85 veneer and squeeze therefrom the surplus moisture which, of course, will pass down over the drain board 7 into the tank 4, as well as compress the veneer sheet to a given thickness. In the circumference of each 90 roller 8 is a knife 10 which extends from end to end of the roller and is so disposed that at the end of a complete revolution of the rollers the knives will come together and shear through the veneer so that it will be 95 divided into sheets of uniform length. The sheets passing from the rollers 8 will be 100 caught and piled upon a table 11, as indicated in Fig. 1^a. This table 11 is disposed near a drier, indicated conventionally at 12, 105 in which the sheets are placed so that all moisture may be driven off. From the drier, the sheets are taken and placed upon a supporting table 13 adjacent which is arranged a press 14 in which the veneer sheets may be 110 placed and firmly clamped, the presser head 15 of this press being provided with parallel

2 slots in which saws or other cutters 16 may operate to divide the sheets of veneer into strips of uniform width. The saws, of course, may be mounted and driven in any 5 convenient manner. The strips thus produced are placed on edge within a hopper or feed box mounted upon a match machine and by the operation of that machine are cut into splints which are fed directly into 10 a carrier which operates as hereinbefore stated.

It will be readily noted that in the practice of my present invention the veneer is 15 impregnated before it is cut into sheets, and these sheets are dried before being cut into strips of a width corresponding to the length of the splints which are to be finished as matches. No large drying drums are required in the practice of my invention 20 and it is not necessary to employ any mechanism for arranging the splints in proper relation to be secured in the carrier inasmuch as they may be fed directly into the carrier as they are formed and they are 25 formed in the proper position and relation to be engaged at once by the carrier. Moreover, the time required to produce the splints is very materially lessened and the 30 cost of production is likewise materially reduced.

Having thus described the invention, I claim:

1. The method of preparing stock for 35 match splints which consists in forming veneer from a body of wood, impregnating the veneer, dividing the impregnated veneer into sheets, drying the sheets, and then cutting the sheets into strips.

2. The method of preparing veneer for 40 match splints which consists in impregnating the veneer as it is produced, draining

from the impregnated veneer the surplus moisture, dividing the impregnated veneer into sheets, drying the sheets, and dividing the dried sheets into strips.

45

3. The method of preparing stock for match splints which consists in producing veneer, impregnating the veneer, expressing surplus liquid from the impregnated veneer and smoothing the surfaces of the veneer, dividing the veneer into sheets, drying the sheets, and dividing the dried sheets into strips.

50

4. Apparatus for producing veneer stock for match splints consisting in a supporting table upon which veneer may be supported, a tank arranged adjacent the supporting table and adapted to contain an impregnating composition through which the veneer may be caused to travel, a drain board at 60 the exit end of the tank to support the impregnated veneer and return to the tank the surplus compound, means receiving the veneer from the drain board for compressing the veneer and dividing it into sheets, a drier, and means for dividing dried sheets into strips.

65

5. An apparatus for the purpose set forth comprising a supporting table to receive and support veneer as it is produced, a tank 70 arranged adjacent the table and through which the veneer may travel, a drain board inclining upwardly from the discharge end of the tank and supporting the veneer passing therefrom, smoothing rollers adjacent 75 the drain board receiving and compressing the veneer, and knives mounted in said rollers to divide the veneer into sheets of uniform length.

In testimony whereof I affix my signature.

HARRY KELLEY.
